UNITED STATES PATENT OFFICE

NATHANIEL E. LOOMIS, ALBERT H. TOMLINSON, AND FRANK A. HOWARD, OF ELIZABETH, NEW JERSEY, ASSIGNORS TO STANDARD OIL DEVELOPMENT COMPANY, A CORPORATION OF DELAWARE

ART OF PYROLYSIS

Application filed May 31, 1923. Serial No. 642,400.

This invention relates to the art of pyrolytic conversion of hydrocarbons to lower boiling products, and will be fully understood from the following description, taken in connection with the accompanying drawing, which represents semi-diagrammatically a form of apparatus contemplated in the invention.

Where, in existent procedure, oils are converted to lower boiling products by heating the oil to a cracking temperature in a coil and then transferring the oil to a drum in which a cracking temperature is maintained, there may be a lack of flexible temperature control. Moreover, the highest efficiency desirable at all points is not always realized.

In accordance with the features of the present invention, a close control may be had for cracking in passages largely or wholly dependent upon the contained heat of the oil, in general, and in other aspects there is provided a conversion process in which the hydrocarbons are not only heated up to cracking temperature in a heated passageway but are cracked to an optimum extent, and then are transferred to a digesting zone for a continuation of the cracking.

Referring more particularly to the drawing, the reference character A designates a heated conduit or passageway of suitable construction, for example a bank of tubes 1 connected at the ends by cross-over connections 2 from tube to tube and row to row to allow flow of fluid in a consecutive path and arranged in a furnace or otherwise heated. Joined to the first passageway A by a pipe 3 having a check-valve 4 is a further passageway B of suitable construction. This may be for instance in the form of a larger passage or drum if desired, and in any case is guarded against material heat loss, as by being covered with insulation or mounted so as to be bathed by hot gases, as preferred, in order to avoid heat loss. Another drum B' may be also employed if desired, connected so as to be operated either relay-wise or simultaneously with the drum B, it being understood that such duplication of drums is merely a matter of choice, depending upon circumstances. An outlet pipe

7 leads on from the upper portion of the drum or heat-retaining passageway, preferably through a pressure-release valve 8 to any suitable vapor separator C. Condensers are also provided. When desired, a fractional condenser may be built in the same shell above the vapor separator, and in the example illustrated comprises rectifying plates 9 and a collecting pan 10 for collecting heavier condensate for forwarding through a cooling coil 11 to a receiver (not shown). A vapor pipe 12 leads to a final condenser 13 and receiver (not shown).

Thermometers and pressure gauges are applied at points in the system as desired.

A feed pump 14 serves to supply feed oil to the system, and the feed line 15 leads, for example through a heat exchanger 16 in the path of the vapors, to the coil A by a pipe 17. Communication across from the feed line to the connection 3 is provided by a branch 18 from the feed line posterior to the heat exchanger and a branch 20 from the cold feed line anterior to the heat exchanger. From the connection 3 a by-pass pipe 22 connects directly to the vapor separator.

Various stocks, from kerosene and gas oil to heavier hydrocarbon materials may be used; the material to be operated upon for conversion to lower boiling products being forwarded by the pump 14 and passed to the heating passageway section A and thence to the digesting passageway section B. As the temperature in the digesting passageway primarily follows that of the heating passageway, if the coil or heating passageway be run at an optimum temperature so far as the operation to be performed therein is concerned, it will often occur that the drum or digesting passageway will tend to run at a temperature higher than desirable for the optimum efficiency of such part of the process. In accordance with the present invention the digesting passageway temperature may be maintained at any desired point below the coil temperature. When the temperature in the digesting passageway shows a tendency to run too high, the valve 19 may be opened up as necessary and the temperature is moderated as required by introduc-

tion of the relatively cooler oil from the branch 18. If still cooler oil is desired, the valve 21 may be opened up as necessary. Thus by drawing on one or the other or both feed line branches as preferred and introducing the relatively cooler fluid the temperature in the digesting passageway may be controlled as desired. While two branches, tapping the feed line anterior to and posterior to the heat exchanger are advantageous, it will be understood that the invention contemplates in its simplest form one such branch from the feed line irrespective of the presence or absence of a heat exchanger. Meters M may be placed in the branches to permit measurement of such feed. While the introduction of feed stock into the second or digesting section of a conversion system as described makes possible a temperature control of the digesting zone separately from that of the first portion of the conversion system, it at the same time allows the utilization of excess heat brought from the first zone to convert additional quantities of stock which may be introduced into the second zone and correspondingly produces an efficient throughput.

As an example of some temperatures obtainable in a system according to the foregoing:

Operating at a pressure of 350 lbs. per square inch, (this being the pressure in B), on a mid-continent gas oil of 34° Bé., the coil outlet showed 890° F. With this, the temperature of the products leaving the passageway B was around 820° F. By suitably opening up on the direct feed line branch 18 to the passageway B however, the temperature was controlled to 760° F.

In operating according to the desired detail of our process, the hydrocarbon material to be converted is passed through the heating zone A at a rate, temperature and pressure to secure optimum conditions for cracking therein. A conversion in the coil or heating zone may be readily secured if desired to the extent of more than half of the total amount for the system, for instance. Preferably, although not necessarily, the temperature-pressure condition will be such that the hydrocarbons as subjected to conversion in the coil or heating passageway will be substantially completely in vaporous form. From the actively heated zone these hydrocarbons largely in the form of vapors then proceed to the succeeding passageway or zone guarded against heat loss externally, where the conversion process or digestion continues. By admitting relatively cooler stock also to the digesting zone the temperature may be held down here as desired and such additional stock subjected to conversion. The temperature of the digesting zone is preferably regulated, as described, so as to cause condensation of a substantial pro-

portion of the vapors coming from the heating passageway. Under these conditions the latent heat of vaporization of these condensed bodies is made use of for the heating and conversion of the relatively cooler stock admitted directly to the digesting zone. The optimum temperature for the digestion zone depends upon the character of the hydrocarbons fed to the system and on the pressure. In general the preferred temperature is that which will maintain in the liquid phase those hydrocarbons in the mixture boiling above 450° F. and permit vaporization of the hydrocarbons boiling below 450° F. (at atmospheric pressure). Under these conditions the converted products leaving the digesting zone will consist of a mixture of vaporized light hydrocarbons and fixed gas with heavier hydrocarbons in the liquid phase. It will be understood that there will exist a small proportion of the light hydrocarbons in solution in the liquid phase in the heavier hydrocarbons, and a small proportion of heavier hydrocarbons in the vapor phase, this overlap being a necessary incident of the character of the mixture.

From the digesting zone the products all proceed preferably through a pressure release valve to the vapor separator, where vapors are separated and pass up to the condensers, higher boiling constituents condensing out first and being collected by the pan 10, while lighter products pass on to the final condenser. Ordinarily the digesting zone or zones will be full of liquid oil up to the level of the outlet pipe 7. Under these conditions all fluid products (vapors and liquids, with or without suspended solids) pass together through that pipe to the vapor separator. Under some conditions, however, vapor alone or liquid alone may be withdrawn. Residuum may be taken off from the bottom of the vapor separator by the pipe 25.

By opening up the valve 23 and closing the valve 24 the hot products from the coil A may be by-passed direct to the vapor separator. This is advantageous in particular in emergencies. With valves 23 and 24 both open the digesting passageway may be drained out into the vapor separator. A pump may be placed in the line 22 if desired.

For introducing the cooler hydrocarbon feed into the second zone or digesting passageway, if preferred instead of tapping off a branch from the feed line, an additional line from a separate feed source may be provided.

While the supplemental feed or temperature control feature is particularly advantageous in operating by heating and cracking to an optimum extent and largely or wholly in the vapor phase in a heated passageway and then passing the hydrocarbons to a further digesting passageway, the described procedure is of some merit, for regulative pur-

pose at least, wherever hydrocarbons are heated in one zone and allowed to digest in another zone, irrespective of how much or how little cracking, or vaporization is accomplished in the heating zone.

5 Although we have described our invention by reference to certain specific details, it will be understood that this is for the purpose of illustration, and that changes may be made 10 which come within the spirit and scope of the invention.

What we claim is:

1. In apparatus of the character described, the combination of a coil, means for heating 15 said coil, an enlarged digesting passageway having provision against material temperature loss, a connecting pipe between said coil and the enlarged digesting passageway, a check-valve in said connecting pipe, a vapor 20 separator, a connecting pipe between the upper portion of said enlarged digesting passageway and the vapor separator, a pressure release valve in the last named connecting pipe, a feed pipe connecting through a heat 25 exchanger to the coil first mentioned, branch pipes from the feed pipe anterior and posterior to the heat exchanger and connecting respectively to the digesting passageway, and a by-pass pipe leading from the coil around 30 the digesting passageway to the vapor separator.

2. In apparatus of the character described, the combination of a heating conduit, a digesting passageway connecting therewith 35 and having provision against material temperature loss, a check-valve between said conduit and said digesting passageway, a vapor separator connecting with the upper portion 40 of the digesting passageway, a feed pipe connecting through a heat exchanger to the conduit first mentioned, branch pipes from the feed pipe anterior and posterior to the heat 45 exchanger and connecting respectively to the digesting passageway, and a by-pass pipe leading from the conduit around the digesting 50 passageway to the vapor separator.

3. In apparatus of the character described, the combination of a heating conduit, a digesting passageway connecting therewith and 55 having provision against material temperature loss, a check-valve between said conduit and said digesting passageway, a feed pipe connecting through a heat exchanger to the conduit first mentioned, branch pipes 60 from the feed pipe anterior and posterior to the heat exchanger and connecting respectively to the digesting passageway, and a by-pass pipe leading from the conduit around the digesting 65 passageway.

4. In apparatus of the character described, the combination of a heating conduit, a digesting passageway connected therewith and 70 having provision against material temperature loss, a check-valve between said conduit and said digesting passageway, a feed pipe

connecting to the conduit first mentioned, a branch pipe from the feed pipe connecting to the digesting passageway, and a by-pass pipe leading from the conduit around the digesting passageway.

5. In apparatus of the character described, the combination of a heating conduit, a digesting passageway connected therewith and 75 having provision against material temperature loss, a check-valve between said conduit and said digesting passageway, a feed pipe connecting to the conduit first mentioned, means for supplying relatively cool oil to the digesting passageway as desired, a rectifying tower and a by-pass pipe from said heating 80 conduit around the digesting passageway and leading directly to the rectifying tower.

6. The improvement in the art of pyrolytic conversion under pressure of hydrocarbon oils to lower boiling products, which 85 comprises flowing a stream of the hydrocarbons through a heating zone under conditions of temperature, pressure, and time such as to give substantial cracking and substantial vaporization, then through a zone in 90 which the oil is held for a relatively longer time, introducing relatively cool oil into the last mentioned zone to hold a temperature therein substantially lower than the temperature in the first zone but not below an effective cracking temperature, and withdrawing substantially all the fluid products together 95 from the last mentioned zone.

7. The improvement in the art of pyrolytic conversion of hydrocarbons to lower 100 boiling products, which comprises heating a stream of the hydrocarbons in a heating zone and effecting substantial cracking therein, then allowing further cracking in a chamber separate from the zone in which the 105 aforesaid heating occurred, while controlling the temperature in the said chamber by introducing therein a relatively cool hydrocarbon oil, and withdrawing substantially all the fluid products together from the upper 110 portion of said chamber.

8. The improvement in the art of pyrolytic conversion of hydrocarbons to lower boiling products, which comprises heating the hydrocarbons and effecting substantial cracking, allowing cracking to continue in a digestion zone solely on the acquired heat, while 115 controlling the temperature by introducing fluid hydrocarbons cooler than the heated hydrocarbons, and withdrawing substantially 120 all the fluid products together from the digestion zone.
